DOOR LOCK

John H. Roethel, Detroit, Mich., assignor to
 Roethel Engineering Corporation, Detroit,
 Mich., a corporation of Michigan

Application June 24, 1946, Serial No. 678,991

30 Claims. (Cl. 292—229)

1

This invention relates to latch mechanism for swinging doors and particularly, although not exclusively, to latch mechanism which is especially adapted to be used in connection with the doors of vehicle bodies, such as automobile bodies. An object of the invention is to provide a door latch which combines in relatively simple and compact form such desirable features as quietness of operation when closing the door, simplicity and compactness in construction, operational efficiency and economy in manufacture.

Another object of the invention is to provide an improved door latch embodying a latch bolt extending longitudinally at the free edge of the door and shiftable bodily in a generally vertical or up and down direction by a rotative motion both when closing and opening the door, means being provided for locking or holding the bolt preferably in a plurality of positions and additional means of an improved, relatively simple and efficient character being provided for releasing the bolt locking means selectively from the inside and outside of the door to permit the door to be opened.

Another object of the invention is to provide an improved door latch mechanism for a swinging door, said latch mechanism having a movable latch unit supported for movement between a door latched position and a door unlatched position and being spring urged at all times toward said door unlatched position but being controlled by a movable detent adapted releasably to maintain said latch unit in door latched position, the latch mechanism being provided with improved locking means for preventing release of said latch unit for movement by the spring means from door latched position to door unlatched position, said locking means having a latch unlocked position and a latch locked position, said latch mechanism being provided with means effective when said latch unit is out of door latched position for holding the locking means out of latched locked position in an intermediate position, and a further means, effective when said locking means is in said intermediate position for moving said locking means from said intermediate position into said locked position upon movement of said latch unit into door latched position.

In accordance with the embodiments of the invention, herein illustrated by example, there is provided a movable latch unit mounted on a support for the latch mechanism. The latch unit is movable between a door latched position and a door unlatched position and is under the

2

influence of a spring means urging the latch unit at all times toward door unlatched position. A pivotally movable detent is provided which is adapted releasably to maintain the latch unit in door latched position, the detent having a latch released position and a latch holding position. An outer manually operable lever is provided which is operable to release or move the detent from latch holding position. Preferably the release lever is fixed to the detent and is pivotally mounted on said support to swing about a common pivot axis therewith. A locking means is also provided which is engageable with the release lever for blocking the same and thereby preventing movement of the detent to release the latch unit for movement from door latched to door unlatched position. The locking means is selectively movable into and out of release lever locking position by manually operable means. The latch mechanism is further provided with means for engaging and blocking the locking means against movement into locked position when the latch unit is in door unlatched position, said blocking means being rendered ineffective to block movement of the locking means upon movement of the latch unit from door unlatched to door latched position. An important feature of the present invention is a means, effective when said locking means is engaged and blocked by said blocking means, for automatically moving said locking means into locked position upon movement of said latch unit into door latched position.

Other objects of this invention will appear in the following description and appended claims, reference being had to the accompanying drawings forming a part of this specification wherein like reference characters designate corresponding parts in the several views.

Fig. 1 is a fragmentary side elevation of a portion of an automobile body provided with a swinging front door upon which the latch device made in accordance with the present invention is installed.

Fig. 2 is an enlarged vertical section taken substantially through lines 2—2 of Fig. 1 looking in the direction of the arrows.

Fig. 2A is a face view illustrating in detail the rotatable bolt carrying plate and locking detent or dog therefor.

Fig. 3 is a view in elevation of the latch device taken substantially from position 3 in Fig. 2 looking in the direction of the arrow.

Fig. 4 is a horizontal section taken substan-

tially through lines 4—4 of Fig. 3 looking in the direction of the arrows.

Fig. 5 is a fragmentary horizontal section taken substantially through lines 5—5 of Fig. 3 looking in the direction of the arrows.

Fig. 6 is a fragmentary horizontal section taken substantially through lines 6—6 of Fig. 3 looking in the direction of the arrows.

Fig. 7 is a fragmentary horizontal section taken substantially through lines 7—7 of Fig. 3 looking in the direction of the arrows.

Fig. 8 is a plan view taken substantially from position 8 of Fig. 3 looking in the direction of the arrow.

Fig. 9 is a vertical section taken substantially through lines 9—9 of Fig. 3 looking in the direction of the arrows, this view illustrating the positions of the latch bolt and wedge device when the door is in fully closed position.

Fig. 10 is a view similar to Fig. 9 illustrating the latch bolt and wedge device in their positions when the door is in a partially closed position.

Fig. 11 is a view similar to Fig. 9 illustrating the positions of the latch bolt and wedge device just prior to their engagement with the striker device.

Fig. 12 is a section taken substantially through lines 12—12 of Fig. 9 looking in the direction of the arrows.

Fig. 13 is a section taken substantially through lines 13—13 of Fig. 9 looking in the direction of the arrows.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there is illustrated, by way of example, one embodiment of the present invention as applied to a door and door frame structure, such as that of an automobile body. As illustrated in Fig. 1, the automobile body, designated generally at A, is provided with a front door B which is hinged at its front edge so as to swing against a door post or body pillar C in accordance with conventional practice. The door comprises an outer metal door panel 20 and an inner metal door panel 21, see Fig. 2. The panel 21 terminates in a transverse jamb edge or portion 22 (Fig. 8) facing the fixed jamb face or edge 23 (Fig. 3) of the door frame post or body pillar C.

Secured by means of screws 24 to the inner side of the jamb portion 22 of the door is a case plate 25 having a flange 26 engaging the inner side of the inner door panel 21. Mounted on the case plate 25 is a bolt carrying plate or member 27 which is rotatable upon a pivot or stud 28 in the form of a shoulder rivet secured to the case plate. Rigidly fastened to the plate member 27 at a point spaced from the pivotal axis 28 thereof is a cylindrical latch bolt 29. This bolt is carried by the plate 27 eccentrically thereof and projects outwardly in a longitudinal horizontal direction through an arcuate slot 30 in the case plate and also through a similar and registering arcuate slot in the jamb face 22 of the door. These slots are covered and closed by the plate 27 when the door is open. The bolt carrying plate 27 is formed on its periphery at the

inner side of the pivot 28 with spaced abutments or shoulders 31 and 32 having inclined or curved detent or dog engaging surfaces. The abutment 31 forms the safety locking position or step of the bolt. The abutment 32 is formed deeper than the abutment 31 and provides the final locking position or step of the bolt.

Associated with the bolt carrying plate 27 is a detent arm or dogging member 33 extending in the plane of the plate 27 and located therebelow. This arm 33 is riveted at 34 at an intermediate point to a laterally embossed or offset portion 35a formed in the lower end of a detent actuating lever 35, this lever being pivoted at its lower end so as to swing inwardly and outwardly about a pivot stud or shoulder rivet 36 secured to the case plate and to the embossed portion 35a of the lever. The upper end of the detent actuating lever 35 is guided in its swinging movement by means of a headed stud or pin 37 extending through a guide slot 38 in a laterally embossed or offset portion 35b of the lever. The embossed or offset portions 35a and 35b of the lever 35 enable these portions of the lever to be positioned against or proximate to the case plate 25 while spacing the intermediate portion of the lever away from the case plate so as to provide clearance for the bolt carrying plate 27 and the main spring controlling the same.

It will be noted that the bolt carrying plate 27, as viewed in Fig. 2, is rotatable in a clockwise direction when the bolt moves from unlatched position to its latching position shown in Fig. 2. The detent actuating lever 35 is pivoted at 36 below the bolt carrying plate 27, and the outer end of the detent arm 33 is provided with a dog or detent portion 33a engageable successively with the abutments 31 and 32 when the door is closed. The detent actuating lever 35 is preferably formed from sheet steel in a single stamping and is suitably flanged along certain of the edges thereof to afford the necessary strength and rigidity.

The bolt carrying plate 27 is constantly urged toward bolt unlatching position and the detent arm 33 is constantly urged toward the plate 27 by means of a common main spring 39. This spring in the present instance has a plurality of intermediate coils terminating at one end in an outward extension 39a anchored at its upper end to a tongue 40 struck out from the metal of the lever 35. The main spring also terminates at its opposite end in an upward extension 39b anchored at 41 to the plate 27 at a point above the pivot 28 thereof. The spring 39 is installed under predetermined load or tension so as to exert constant rotative effort on the bolt carrying plate 27 and the detent actuating lever 35. It will be seen that by mounting and connecting the main spring as shown the spring will resist inward movement, i. e. to the left in Fig. 2, of the lever 35 and will also resist rotative motion of the bolt carrying plate 27 in a clockwise direction, i. e. toward bolt latching position. From this construction it will be seen that a single spring means may be utilized to control the bolt carrying plate 27 and the detent actuating lever 35, this spring providing a direct connection between these parts. The outer edge of the lever 35 is formed with a lateral flange or extension 35c providing an enlarged widened surface well above the pivot or fulcrum 36 for engagement by a plunger 42 which may be shifted inwardly by means of a pull-out handle 43 or by any other suitable means such as a push button operable from the outside of the door.

In accordance with the present invention improved remote control mechanism is provided for swinging the lever 35 and detent arm 33 into position to disengage the detent arm from either the safety step or abutment 31 or the final step or abutment 32. This remote control mechanism includes manually operable means, such as a door handle or push button device, located on the inside of the door at a point remote from the case plate. The remote control mechanism comprises a bell crank or two arm lever 44 pivoted at 45 through the medium of a shoulder rivet to the case plate flange 26, see Fig. 3. The bell crank 44 includes a longitudinally extending offset arm 44a notched at its outer end to overlie a lateral flange 33b formed at the terminal end of the detent arm 33, see Figs. 2, 3 and 4. The lever 44 also has a depending lever arm 44b connected by a stud 46 to the slotted end 47 of a remote control link 48 which is pivoted at its opposite end at 48a to the lower end of a swinging lever 49. The upper end of this lever is pivoted at 50 to a mounting plate 51 secured to the inner door panel 21. The lever is secured at its pivot 50 to the shank of the inner door handle (not shown) and is provided with an upward projection 49a engaged by a spring 52 effective to return the lever to its normal position after the inner door handle has been released. By turning the inner door handle to rock the lever 49 the link 48 will be shifted to the left in Fig. 3, thus rocking the bell crank lever 44, depressing the lever arm 44a which by engagement with the flanged end 33b of the detent arm 33 will force the detent downwardly from its position shown in Fig. 2 until the dog portion 33a thereof clears and is free of the abutment 31 or 32 on the bolt carrying plate 27. When this action occurs the spring 39 will rotate the plate 27 in a counterclockwise direction thereby shifting the bolt 29 to the lower end of the slot 30 in the case plate. A similar action occurs when the plunger 42 is shifted inwardly to rock the lever 35. It will be apparent from this construction that actuation of either the plunger 42 or remote control lever 44 to free the detent from the plate 27 will be accomplished one independent of the other.

In accordance with the present invention additional means is provided for locking the bolt carrying plate 27 when this plate as well as the latch bolt 29 has been moved to the final locking position with the detent or dog portion 33a in engagement with the abutment or final locking step 32 shown in Fig. 2. This additional locking means comprises a bell crank or two arm locking lever 53 pivoted at 54 to the case plate flange 26 by means of a shoulder rivet, see Fig. 3. The locking lever has a depending arm 53a stamped to form an intermediate embossed portion or blocking projection 53b which, as shown in Figs. 2 and 7, is arranged in such manner as to be shifted into and out of blocking position with respect to an inner flanged edge portion 35d of the detent actuating lever 35. The inside locking lever 53 is also formed with a longitudinally extending arm 53c lying against the inner face of the case plate flange 26 and pivotally connected at its terminal end to a vertically extending rod or plunger 55. This rod projects through the garnish molding at the lower edge of the window opening and carries at its upper end a knob or button 56 (see Fig. 1) which is accessible at the inner side of the window glass of the door. It will be readily seen that when the knob or button 56 is pulled up-

wardly the rod or link 55 will swing the lever 53 about its pivot 54 thereby shifting the blocking projection 53b to the position shown in Fig. 3 and the full line position shown in Fig. 7 out of blocking position with respect to the flange portion 35d of the detent actuating lever 35. When, however, the knob or button 56 is pushed down to shift the rod 55 downwardly from the position shown in Fig. 3, the depending arm 53a of the lever will be swung forwardly thereby shifting the blocking projection 53b to the dotted line position shown in Fig. 7 into blocking or abutting relation with respect to the lever 35. When this occurs the lever will be blocked against swinging motion in a counter-clockwise direction as viewed in Fig. 2, and any attempt to release the detent arm 33 from the bolt carrying plate 27 by shifting the plunger 42 through the medium of the outer door handle 43 or swinging the remote control lever 44 through the medium of the inner door handle will be prevented. In other words, when the blocking projection 53b is moved into blocking position with respect to the detent actuating lever 35, the door cannot be opened by manipulating either the inner door handle or the outer door handle.

The inside locking lever 53 may also be actuated by means of a key controlled device from the outside of the door, such device being ordinarily incorporated in one or both of the front door locks but usually omitted in connection with the rear door locks of the vehicles. As illustrated in Fig. 3 the lower end of the arm 53a of the locking lever 53 is provided with a vertical slot 57 within which is slidable a pin 58 attached to the upper end of a crank arm 59 pivoted at its lower end to the case plate, the lever being provided with a square opening or socket to receive a key actuated shaft 60. The shaft is connected to the cylinder mechanism of any conventional lock having the usual key control. By turning the key in the lock in the outside of the door the crank arm 59 may be swung from the position shown in Fig. 3 in a clockwise direction thereby swinging the arm 53a and shifting the blocking projection 53b to its blocking position shown in dotted lines in Fig. 7. Reverse turning of the key will swing the lever arm 53a in the opposite direction to the position shown in Fig. 3 and in full lines in Fig. 7, thereby moving the blocking projection 53b out of blocking position with respect to the detent actuating lever 35.

The inside locking lever 53 is yieldingly controlled by means of a snap-over spring 61 comprising an intermediate coiled portion, one end of the spring being anchored at 61a to the case plate and the other end anchored at 61b to the lever arm 53c. This spring will yieldingly hold the lever 53 in either its blocking or unblocking position by reason of the fact that the point 61b passes above and below dead center when the lever is shifted to unblocking and blocking positions respectively.

It will be seen that the latch bolt 29 is movable between unlatching and latching positions in an arcuate path as defined by the arcuate slot 30 in the case plate. The bolt is actuated when the door is closed by means of a striker device which is mounted on the jamb edge 23 (Fig. 3) of the body pillar or fixed upright member of the door frame. In the present instance the striker device comprises a stamped metal piece 62 flanged entirely around its edges to provide strength and rigidity. This striker member 62 is adapted to be secured to the jamb edge of the

pillar or door frame by screws 63, and is formed with an inwardly and upwardly extending slot or guideway 64 which in the present instance has straight parallel sides 64a and 64b formed by the flanging of the edges of the striker so as to afford ample bearing engagement with the bolt 29 as clearly shown in Fig. 3. The width of the guideway 64 approximates the diameter of the bolt 29 and usually is slightly greater in order to ensure free movement of the bolt through the guideway regardless of variations due to allowable tolerances in production.

In the present embodiment of the invention I provide yieldable wedging means cooperable with the striker casing 62 and also with the bolt to hold the door rigidly against vertical vibratory motion during operation of the vehicle, see Figs. 9 to 13 inclusive. This wedging means in the present instance comprises a stamped hollow casing 65 of generally rectangular shape and open at the bottom. The top wall 65a of the casing projects through a slot in the case plate 25 and is peened over at 65b so as to rigidly secure the casing 65 to the case plate. Extending upwardly within the casing 65 and slideable therein is a wedge block 66, the outer face thereof being notched to receive the outer depending wall 65c of the casing, as shown in Fig. 12. The inner vertical wall of the wedge block is formed with a groove or guide slot 67 extending from end to end and adapted to receive a guide rib 68 pressed out of the metal of the case plate 25. Communicating with the guide slot 67 is a shorter slot 69 which is of a shape and depth to receive a compression spring 70, one end of the spring bottoming against the closed end of the slot 69 and the other end of the spring engaging a wall of the casing 65, as shown in Fig. 13. This spring is mounted under initial load and constantly urges the wedge block 66 toward the position shown in Fig. 10. The top wall of the casing 62 is inclined as shown at 62a and the bottom of the block 66 is correspondingly inclined as shown at 66a.

During closing movement of the door, as the wedge block 66 travels from the position shown in Fig. 11 successively to the positions shown in Figs. 10 and 9, it will engage the inclined surface 62a of the casing and, due to frictional contact, will be forced back to some extent against the action of the spring 70. During vehicle operation and as a result of vibrations incident thereto the wedge will be constantly urged upwardly along the inclined surface 62a by the spring 70 and this action will result in maintaining the bolt 29 firmly in engagement with the upper inclined wall 64a of the bolt guideway 64. Thus, due to the action of the wedge 66 the portion of the striker casing 62 lying between the bolt 29 and the wedge will at all times be rigidly clamped therebetween regardless of the final position taken by the bolt within the guide slot. This position will vary slightly during use of the vehicle due to the fact that the door is usually closed against a marginal rubber weatherstripping which compresses to a variable extent during usage.

In the present embodiment the construction is such as to permit the lever 53 to be moved to blocking position when the detent 33 is engaged with the final locking step 32 but not when engaged with the safety step 31 or when the door is fully open. The bolt plate 27 is provided with an additional abutment 75 having the same depth as the abutment or step 31 and, hence,

shallower than the step 32. When the door is open with the bolt at the lower end of slot 30 the detent portion 33a will engage the step 15. Since this step is shallower than the step 32 it will hold the detent arm a slight distance lower than its position in Fig. 2 and correspondingly will hold the lever 35 a slight distance to the left of its position in Fig. 2. This displacement of the lever 35 will be sufficient to project the edge 10 of the abutment flange 35d into the path of the blocking projection 52b, as shown in dotted lines in Fig. 7. A similar position of the flange 35d is taken when the detent is engaged in the safety step. When thus positioned it will be seen that the abutment flange 35d will prevent the blocking projection from being shifted past the edge of the flange to blocking position.

The spring 61 may be mounted so as to return the lever 53 to normal position, shown by the full lines in Figs. 3 and 7, except when the blocking projection moves into blocking position, or may be mounted as shown in Fig. 7 so as to throw the lever into blocking position when the door is swung closed after first pushing down on the knob 55 in the open position of the door. With the door in open position the knob 55 may be depressed a short distance thus depressing the lever arm 53c and moving the blocking projection against the edge of the flange 35d (the latter being in the dotted line position of Fig. 7). When this occurs the point of connection 61b of spring 61 will pass below dead center a slight distance, thus enabling the spring to hold the blocking projection against the flange 35d. If the door is then slammed or swung closed, movement of the detent into the final step 32 will back the flange 35d out of the path of the blocking projection 52b to the full line position of Fig. 7. At the instant this occurs the spring 61 will force the projection 52b to blocking position shown in dotted lines in Fig. 7. Thus, with the foregoing spring arrangement it is possible to close the door from the outside and automatically lock the door without requiring the use of the key.

The step 15 on the bolt plate has the additional advantage of ensuring that the bolt 29 will at all times assume a predetermined position when the door is open. Any upward shifting of the bolt when the door is open will be resisted by the spring loaded detent which will at all times urge the bolt plate to full unlocked position with the detent in full engagement with step 15. This action assists in maintaining the bolt in proper position with respect to the open end of the striker slot 64.

To ensure rapid and positive engagement of the detent with the final locking step when the door is slammed I prefer to provide an additional coil spring 76 to assist the main spring 39. The inner end of spring 76 is anchored to a struck-out tongue 77 on the case plate and the outer end 76a engages the underside of the detent arm 33 thus urging it upwardly toward locking position.

I claim:

1. In a door control mechanism a movable latch unit supported for movement between a door latched position and a door unlatched position, spring means for urging said latch unit at all times toward said door unlatched position, a movable detent adapted releasably to maintain said latch unit in door latched position and having a latch released position and a latch holding position, locking means for preventing release of said latch unit for movement by said

spring means from door latched position to door unlatched position, said locking means having a latch unlocked position and a latch locked position, means effective when said latch unit is out of door latched position for holding said locking means out of latch locked position in an intermediate position, and means, effective when said locking means is in said intermediate position, for moving said locking means from said intermediate position into said locked position upon movement of said latch unit into door latched position.

2. In a door control mechanism, a latch unit supported for movement between a door latched position and a door unlatched position, a movable detent adapted releasably to maintain said latch unit in door latched position and having a latch released position and a latch holding position, means for actuating said detent to release said latch unit from door latched position, locking means for preventing release of said latch unit from door latched position, manually operable means for selectively moving said locking means into and out of a locked position in which release of said latch unit from door latched position is prevented, means for engaging and blocking said locking means against movement into locked position when said latch unit is in door unlatched position, said blocking means being rendered ineffective upon movement of said latch unit from door unlatched to door latched position, and means, effective when said locking means is engaged and blocked by said blocking means, for automatically moving said locking means into locked position upon movement of said latch unit into door latched position.

3. In a door control mechanism a movable latch unit, a movable detent operatively associated with said latch unit, said latch unit having an operative or door latched position and an operated or door unlatched position and being movable therebetween in latching and unlatching directions, said detent having a latch holding position in which it maintains said latch unit in said operative or door latched position and being movable therefrom to a latch released position permitting movement of said latch unit in unlatching direction, a movable locking member having a latch unlocked position, and a latch locked position, and an intermediate position therebetween, blocking means effective when said latch unit is out of door latched position for holding said locking member against movement from said intermediate position into said latch locked position, and means for automatically moving said locking member from said intermediate position into said latch locked position upon movement of said latch unit into door latched position.

4. In a door control mechanism, a movable latch unit, a movable detent operatively associated with said latch unit, said latch unit having an operative or door latched position and an operated or door unlatched position and being movable therebetween in latching and unlatching directions, said detent having a latch holding position in which it maintains said latch unit in said operative or door latched position and being movable therefrom to a latch released position permitting movement of said latch unit in unlatching direction, a movable locking member having a latch unlocked position, a latch locked position, and an intermediate position therebetween, blocking means effective when said latch unit is

out of door latched position for holding said locking member against movement from said intermediate position into said latch locked position, means for automatically moving said locking member from said intermediate position into said latch locked position upon movement of said latch unit into door latched position, and manually operable means for positioning said locking member in either latch unlocked, latch locked, or intermediate position.

5. In a door control mechanism, a movable latch unit, a movable detent operatively associated with said latch unit, said latch unit having an operative or door latched position and an operated or door unlatched position and being movable therebetween in latching and unlatching directions, said detent having a latch holding position in which it maintains said latch unit in said operative or door latched position and being movable therefrom to a latch released position permitting movement of said latch unit in unlatching direction, a movable locking member having a latch unlocked position, and a latch locked position, and an intermediate position therebetween, blocking means effective when said latch unit is out of door latched position for holding said locking member against movement from said intermediate position into said latch locked position, and spring means operatively associated with said locking member and adapted to urge said locking member away from said latch locked position when said locking member is in said latch unlocked position and to urge said locking member toward said latch locked position upon said locking member reaching a point between said latch unlocked position and said intermediate position during movement from latch unlocked position toward latch locked position.

6. In a door control mechanism, a movable latch unit, a movable detent operatively associated with said latch unit, said latch unit having an operative or door latched position and an operated or door unlatched position and being movable therebetween in latching and unlatching directions, said detent having a latch holding position in which it maintains said latch unit in said operative or door latched position and being movable therefrom to a latch released position permitting movement of said latch unit in unlatching direction, a movable locking member having a latch unlocked position, and a latch locked position, and an intermediate position therebetween, blocking means effective when said latch unit is out of door latched position for holding said locking member against movement from said intermediate position into said latch locked position, spring means operatively associated with said locking member and adapted to urge said locking member away from said latch locked position when said locking member is in said latch unlocked position and to urge said locking member toward said latch locked position upon said locking member reaching a point between said latch unlocked position and said intermediate position during movement from latch unlocked position toward latch locked position, and manually operable means for moving said locking member from said latch unlocked position to said intermediate and latch locked positions and return.

7. In a door control mechanism, a movable latch unit, a movable detent operatively associated with said latch unit, said latch unit having an operative or door latched position and an operated or door unlatched position and being

movable therebetween in latching and unlatching directions, said detent having a latch holding position in which it maintains said latch unit in said operative or door latched position and being movable therefrom to a latch released position permitting movement of said latch unit in unlatching direction, a movable locking member having a latch unlocked position, and a latch locked position, and an intermediate position therebetween, blocking means effective when said latch unit is out of door latched position for holding said locking member against movement from said intermediate position into said latch locked position, spring means operatively associated with said locking member and adapted to urge said locking member away from said latch locked position when said locking member is in said latch unlocked position and to urge said locking member toward said latch locked position upon said locking member reaching a point between said latch unlocked position and said intermediate position during movement from latch unlocked position toward latch locked position, and means, manually operable from the inner side of the door with which the mechanism is used, for moving said locking member from said latch unlocked to said intermediate and latch locked positions and return.

8. In a door control mechanism, a movable latch unit, a movable detent operatively associated with said latch unit, said latch unit having an operative or door latched position and an operated or door unlatched position and being movable therebetween in latching and unlatching direction, said detent having a latch holding position in which it maintains said latch unit in said operative or door latched position and being movable therefrom to a latch released position permitting movement of said latch unit in unlatching direction, a movable locking member having a latch unlocked position, a latch locked position, and an intermediate position therebetween, blocking means effective when said latch unit is out of door latched position for holding said locking member against movement from said intermediate position into said latch locked position, and means, including a snap-over spring, for holding said locking member in said intermediate position after being moved thereinto when said latch unit is in door unlatched position and for automatically moving said locking member from said intermediate position into said latch locked position when said latch unit moves from door unlatched into door latched position.

9. In a door control mechanism, a movable latch unit, a movable detent operatively associated with said latch unit, said latch unit having an operative or door latched position and an operated or door unlatched position and being movable therebetween in latching and unlatching directions, said detent having a latch holding position in which it maintains said latch unit in said operative or door latched position and being movable therefrom to a latch released position permitting movement of said latch unit in unlatching direction, a movable locking member having a latch unlocked position, a latch locked position, and an intermediate position therebetween, blocking means effective when said latch unit is out of door latched position for holding said locking member against movement from said intermediate position into said latch locked position, means, including a snap-over spring, for holding said locking member in said

intermediate position after being moved thereinto when said latch unit is in door unlatched position and for automatically moving said locking member from said intermediate position into said latch locked position when said latch unit moves from door unlatched into door latched position, and manually operable means for positioning said locking member in either latch unlocked, latch locked, or intermediate position.

10. In a door control mechanism, a movable latch unit, a movable detent operatively associated with said latch unit, said latch unit having an operative or door latched position and an operated or door unlatched position and being movable therebetween in latching and unlatching directions, said detent having a latch holding position in which it maintains said latch unit in said operative or door latched position and being movable therefrom to a latch released position permitting movement of said latch unit in unlatching direction, a locking member having a latch unlocked position, a latch locked position, and an intermediate position therebetween, locking member blocking means arranged to be moved from blocking to non-blocking position concurrently with movement of said latch unit from door unlatched to door latched position whereby said blocking means is effective to hold said locking member against movement from said intermediate position into said latch locked position when said latch unit is out of door latched position, and spring means for urging said locking member from said intermediate position into said locked position where said latch unit is in door unlatched position and said locking member is moved from said unlocked position into said intermediate position, movement of said latch unit into door latched position and concurrent movement of said blocking means into non-blocking position will permit said spring means to move said locking member from said intermediate position into said locked position.

11. In a door control mechanism, a movable latch unit, a movable detent operatively associated with said latch unit, said latch unit having an operative or door latched position and an operated or door unlatched position and being movable therebetween in latching and unlatching directions, said detent having a latch holding position in which it maintains said latch unit in said operative or door latched position and being movable therefrom to a latch released position permitting movement of said latch unit in unlatching direction, a locking member having a latch unlocked position, a latch locked position, and an intermediate position therebetween, locking member blocking means arranged to be moved from blocking to non-blocking position concurrently with movement of said latch unit from door unlatched to door latched position whereby said blocking means is effective to hold said locking member against movement from said intermediate position into said latch locking position when said latch unit is out of door latched position, spring means for urging said locking means from said intermediate position into said locked position whereby, when said latch unit is in door unlatched position and said locking member is moved from said latch unlocked into said intermediate position, movement of said latch unit into door latched position and concurrent movement of said blocking means into non-blocking position will permit said spring means to move said locking member from said

intermediate position into said locked position, and manually operable means for positioning said locking member in either unlocked, locked, or intermediate position.

12. In a door control mechanism, a movable latch unit, a movable detent operatively associated with said latch unit, said latch unit having an operative or door latched position and an operated or door unlatched position and being movable therebetween in latching and unlatching directions, said detent having a latch holding position in which it maintains said latch unit in said operative or door latched position and being movable therefrom to a latch released position permitting movement of said latch unit in unlatching direction, a locking member having a latch unlocked position, a latch locked position, and an intermediate position therebetween, blocking means for holding said locking member against movement from said intermediate position into said latch locking position when said latch unit is in its operated or door unlatched position, said blocking means being operatively associated with said detent for movement out of position to hold said locking member in its intermediate position concurrently with movement of said detent into latch holding position, and means for urging said locking member away from said latch locked position when said locking member is in said latch unlocked position and toward said latch locked position when in said intermediate position.

13. In combination in a door control mechanism, a latch unit supported for movement between a door latched position and a door unlatched position, a movable detent adapted releasably to maintain said latch unit in door latched position and having a latch released position and a latch holding position, a locking member supported for movement between a latch unlocked position and a latch locked position and having an intermediate position therebetween, lock member blocking means associated with said detent, said locking member having a portion positioned to engage said lock member blocking means when said detent is in latch released position whereby said locking member is held out of latch locked position in said intermediate position, and spring means for urging said locking member away from said latch locked position when in said latch unlocked position and toward said latch locked position when in said intermediate position whereby said locking member, after being moved from said latch unlocked position to said intermediate position, will be moved by said spring means into its latch locked position upon movement of said detent into latch holding position.

14. In a door control mechanism, a frame structure, a latch unit supported by said frame structure for movement between a door latched position and a door unlatched position, a movable detent supported by said frame structure and operatively associated with said latch unit, said detent having a latch holding position and a latch released position, a locking member pivotally supported on said frame structure for movement between a latch unlocked position and a latch locked position, locking member blocking means effective when said latch unit is out of door latched position to block said locking member out of latch locked position in an intermediate position, and spring means extending between said frame and said locking member, the common center line between the

pivotal support of said locking member and the effective point of engagement of said spring means with said frame structure passing between the position of the effective point of engagement of said spring means with said locking member when said locking member is in unlocked position and the position of said effective point of engagement of said spring means with said locking member when said locking member is in said intermediate position, whereby when said locking member is in unlocked position said spring means tends to maintain it therein and, when said locking member is moved from unlocked position toward locked position, said spring means will, after said effective point of engagement of said spring means with said locking member crosses said common center line, urge said locking member toward its said intermediate and latch locked positions.

15. In a door control mechanism, a frame structure, a latch unit supported by said frame structure for movement between a door latched position and a door unlatched position, a movable detent supported by said frame structure and operatively associated with said latch unit, said detent having a latch holding position and a latch released position, a locking member pivotally supported on said frame structure for movement between a latch unlocked and a latch locked position, said detent having a locking member blocking portion movable therewith, said blocking portion being positioned to block said locking member out of latch locked position in an intermediate position when said detent is in latch released position and to permit movement of said locking member into latch locked position when said detent is in latch holding position, and spring means extending between said frame and said locking member, the common center line between the pivotal support of said locking member and the effective point of engagement of said spring means with said frame structure passing between the position of the effective point of engagement of said spring means with said locking member when said locking member is in unlocked position and the position of said effective point of engagement of said spring means with said locking member when said locking member is in said intermediate position, whereby when said locking member is in unlocked position said spring means tends to maintain it therein and, when said locking member is moved from unlocked position toward locked position, said spring means will, after said effective point of engagement of said spring means with said locking member crosses said common center line, urge said locking member toward its said intermediate and latch locked positions.

16. In a door control mechanism, a frame structure, a latch unit supported by said frame structure for movement between a door latched position and a door unlatched position, a movable detent supported by said frame structure and operatively associated with said latch unit, said detent having latch holding position and a latch released position, a locking member supported on said frame structure for lineal movement between a latch unlocked position and a latch locked position, locking member blocking means effective when said latch unit is out of door latched position to block said locking member out of latch locked position in an intermediate position, an actuating lever for said locking member, said lever being pivotally mounted on

said frame, means for operatively connecting said lever to said locking member, and spring means extending between said lever and said frame, said spring means being arranged to urge said lever in a direction to move said locking member away from said intermediate and locked positions when said locking member is in unlocked position and to urge said lever in a direction to move said locking member toward said intermediate and locked positions upon said locking member reaching a point between said unlocked position and said intermediate position during movement from unlocked position toward locked position.

17. Apparatus for locking a door latch mechanism, having a door latched position and a door unlatched position, against release from door latched position comprising, releasable means for non-yieldingly maintaining the latch mechanism in said latched position, a locking member supported for movement between a locked position and an unlocked position, said locking member when in unlocked position permitting release of said door latch mechanism from non-yielding door latched position and when in locked position preventing release of said door latch mechanism from said door latched position, manually operable means for selectively positioning said locking member in either of said two positions, means for holding said locking member out of locked position when said latch mechanism is in door unlatched position, and means, effective when said locking member is held out of locked position, for automatically moving said locking member into locked position upon movement of said latch mechanism into door latched position.

18. In a door control mechanism, a latch unit supported for movement between a door latched position, a secondary latched position, and a door unlatched position, means for releasably holding said latch unit in door latched position, means for releasably holding said latch unit in said secondary latched position, locking means for preventing release of said latch unit from door latched position, said locking means having a latch unlocked position and a latch locked position, means effective when said latch unit is in said secondary latched position or in said door unlatched position for holding said locking means out of latch locked position in an intermediate position, and means, effective when said locking means is in said intermediate position, for moving said locking means from said intermediate position into said locked position upon movement of said latch unit into door latched position.

19. In a door control mechanism, a latch unit supported for movement between a door latched position and a door unlatched position, a positive détent adapted releasably to hold said latch unit in door latched position, said détent having a latch holding position in which said latch unit is positively blocked against unlatching movement and also a latch released position, means for actuating said détent to release said latch unit from door latched position, locking means for preventing release of said latch unit from door latched position, means for automatically moving said locking means into locked position upon movement of said latch unit into door latched position, and manually operable control means for selectively rendering said automatic means effective or ineffective to move said locking means into locked position upon movement of said latch unit into door latched position.

20. In a door control mechanism, a support, a movable latch unit carried by said support for

movement between a door latched position and a door unlatched position, spring means for urging said latch unit at all times toward said door unlatched position, a pivotally movable détent adapted releasably to maintain said latch unit in door latched position and having a latch released position and a latch holding position, an outer manually operable détent release lever pivotally mounted on said support and operable to move said détent from said latch holding position to said latch released position, locking means engageable with said release lever for blocking the same and thereby preventing movement of said détent to release said latch unit, said locking means having a latch unlocked position and a latch locked position, means effective when said latch unit is out of door latched position for holding said locking means out of latch locked position in an intermediate position, and means effective when said locking means is in said intermediate position for moving said locking means from said intermediate position into said locked position upon movement of said latch unit into door latched position.

21. In a door control mechanism, a support, a movable latch unit carried by said support for movement between a door latched position and a door unlatched position, spring means for urging said latch unit at all times toward said door unlatched position, a pivotally movable détent adapted releasably to maintain said latch unit in door latched position and having a latch released position and a latch holding position, an outer manually operable détent release lever pivotally mounted on said support and operable to move said détent from said latch holding position to said latch released position, said détent and said release lever being pivotally mounted on said support to swing about a common pivotal axis, locking means for preventing release of said latch unit for movement by said spring means from door latched position to door unlatched position, said locking means having a latch unlocked position and a latch locked position, means effective when said latch unit is out of door latched position for holding said locking means out of latch locked position in an intermediate position, and means effective when said locking means is in said intermediate position for moving said locking means from said intermediate position into said locked position upon movement of said latch unit into door latched position.

22. In a door control mechanism, a support, a movable latch unit carried by said support for movement between a door latched position and a door unlatched position, spring means for urging said latch unit at all times toward said door unlatched position, a pivotally movable détent adapted releasably to maintain said latch unit in door latched position and having a latch released position and a latch holding position, an outer manually operable détent release lever pivotally mounted on said support and operable to move said détent from said latch holding position to said latch released position, locking means engageable with said release lever for blocking the same and thereby preventing movement of said détent to release said latch unit, said locking means having a latch unlocked position and a latch locked position, means on said release lever effective when said latch unit is out of door latched position for holding said locking means out of latch locked position in an intermediate position, and means effective when said locking means is in said intermediate position for mov-

ing said locking means from said intermediate position into said locked position upon movement of said latch unit into door latched position.

23. In a door control mechanism, a support, a movable latch unit carried by said support for movement between a door latched position and a door unlatched position, spring means for urging said latch unit at all times toward said door unlatched position, a pivotally movable detent adapted releasably to maintain said latch unit in door latched position and having a latch released position and a latch holding position, an outer manually operable detent release lever pivotally mounted on said support and operable to move said detent from said latch holding position to said latch released position, locking means engageable with said release lever for blocking the same and thereby preventing movement of said detent to release said latch unit, said locking means having a latch unlocked position and a latch locked position, means effective when said latch unit is out of door latched position for holding said locking means out of latch locked position in an intermediate position, and spring means effective when said locking means is in said intermediate position for moving said locking means from said intermediate position into said locked position upon movement of said latch unit into door latched position.

24. In a door control mechanism, a support, a movable latch unit carried by said support for movement between a door latched position and a door unlatched position, spring means for urging said latch unit at all times toward said door unlatched position, a pivotally movable detent adapted releasably to maintain said latch unit in door latched position and having a latch released position and a latch holding position, an outer manually operable detent release lever pivotally mounted on said support and operable to move said detent from said latch holding position to said latch released position, said detent and said release lever being pivotally mounted on said support to swing about a common pivotal axis, locking means for preventing release of said latch unit for movement by said spring means from door latched position to door unlatched position, said locking means having a latch unlocked position and a latch locked position, means on said release lever effective when said latch unit is out of door latched position for holding said locking means out of latch locked position in an intermediate position, and spring means effective when said locking means is in said intermediate position for moving said locking means from said intermediate position into said locked position upon movement of said latch unit into door latched position.

25. In a door control mechanism, a latch unit supported for movement between a door latched position and a door unlatched position, a movable detent adapted releasably to maintain said latch unit in door latched position and having a latch released position and a latch holding position, means for actuating said detent to release said latch unit from door latched position, said last mentioned means and said detent being swingable about a common pivot axis, locking means for preventing release of said latch unit from door latched position, manually operable means for selectively moving said locking means into and out of a locked position in which release of said latch unit from door latched position is prevented, means for engaging and blocking said locking means against movement into locked position when said latch unit is in door unlatched position,

said blocking means being rendered ineffective upon movement of said latch unit from door unlatched to door latched position, and means, effective when said locking means is engaged and blocked by said blocking means, for automatically moving said locking means into locked position upon movement of said latch unit into door latched position.

26. In a door control mechanism, a latch unit supported for movement between a door latched position and a door unlatched position, a movable detent adapted releasably to maintain said latch unit in door latched position and having a latch released position and a latch holding position, means for actuating said detent to release said latch unit from door latched position, said last mentioned means including a member swingable with said detent about a common pivot axis, locking means for preventing release of said latch unit from door latched position, manually operable means for selectively moving said locking means into and out of a locked position in which release of said latch unit from door latched position is prevented, means for engaging and blocking said locking means against movement into locked position when said latch unit is in door unlatched position, said blocking means being rendered ineffective upon movement of said latch unit from door unlatched to door latched position, and means, effective when said locking means is engaged and blocked by said blocking means, for automatically moving said locking means into locked position upon movement of said latch unit into door latched position.

27. In a door control mechanism, a latch unit supported for movement between a door latched position and a door unlatched position, a positive detent adapted releasably to hold said latch unit in door latched position, said detent having a latch holding position in which said latch unit is positively blocked against unlatching movement and also a latch released position, means for actuating said detent to release said latch unit from door latched position, said last mentioned means including a member attached to said detent for movement therewith about a common pivot axis, locking means for preventing release of said latch unit from door latched position, means for automatically moving said locking means into locked position upon movement of said latch unit into door latched position, and manually operable control means for selectively rendering said automatic means effective or ineffective to move said locking means into locked position upon movement of said latch unit into door latched position.

28. In a door control mechanism, a support, a movable latch unit carried by said support for movement between a door latched position and a door unlatched position, a lever means mounted on a pivot stud affixed to said support and including a detent portion adapted releasably to maintain said latch unit in door latched position and having a latch released position and a latch holding position, said lever means having a first part adapted to be engaged by outer manually operable means and a second part adapted to be engaged by inner manually operable means, both of said manually operable means being operable to move said detent portion from said latch holding position to said latch released position, locking means engageable with said lever means for blocking the same and thereby preventing movement of said detent portion to release said latch unit, said locking means having a latch unlocked position and a latch locked position, means effec-

tive when said latch unit is out of door latched position for holding said locking means out of latch locked position in an intermediate position, and means effective when said locking means is in said intermediate position for moving said locking means from said intermediate position into said locked position upon movement of said latch unit into door latched position.

29. In a door control mechanism, a support, a pivotally movable latch unit carried by said support for movement between a door latched position and a door unlatched position, said latch unit including a plate member having spaced safety and final locking steps, said safety locking step having less effective depth than the final locking step, a lever swingably mounted on said support and having a detent portion rigid therewith, said detent portion being releasably engageable with either of said locking steps to hold said latch unit in door latched position, said lever having at its outer edge a lateral flange engageable by an outer manually shiftable plunger adapted to swing said lever to move said detent portion from a latch holding position to a latch released position, said lever having a latch released position, an intermediate position when said detent portion is in engagement with said safety locking step, and a final latch locked position when said detent portion is in engagement with said final locking step, locking means having a latch locked position and a latch unlocked position and engageable with said lever when the latter is in final latch locked position for blocking the same to thereby prevent movement of said detent portion out of holding position relative to said final locking step, said lever when in said latch released position or said intermediate position having a portion thereof blocking movement of said locking means from its latch unlocked position to its latch locked position.

30. In a door control mechanism, a support, a pivotally movable latch unit carried by said support for movement between a door latched position and a door unlatched position, said latch unit including a plate member having spaced safety and final locking steps, said safety locking step having less effective depth than the final locking step, a lever swingably mounted on said support and having a detent portion rigid there-

with and also a blocking portion, said detent portion being releasably engageable with either of said locking steps to hold said latch unit in door latched position, said lever having at its outer edge a lateral flange engageable by an outer plunger operator adapted to swing said lever to move said detent portion from a latch holding position to a latch released position, said lever having a latch released position, an intermediate position when said detent portion is in engagement with said safety locking step, and a final latch locked position when said detent portion is in engagement with said final locking step, a locking lever pivotally mounted on said support and having a latch locked position and a latch unlocked position and also having a portion engageable with said blocking portion when said lever is in final latch locked position for blocking the same to thereby prevent movement of said detent portion out of holding position relative to said final locking step, said lever when in said latch released position or said intermediate position having a portion thereof blocking movement of said locking means from its latch unlocked position to its latch locked position.

JOHN H. ROETHEL.
